UNITED STATES PATENT OFFICE.

WILLIAM HARDY, OF DUNDAS, ONTARIO, CANADA.

BACK-BAND FOR HARNESS.

SPECIFICATION forming part of Letters Patent No. 317,346, dated May 5, 1885.

Application filed March 11, 1885. (No model.)

To all whom it may concern:

Be it known that I, WILLIAM HARDY, of the town of Dundas, in the county of Wentworth, in the Province of Ontario, Dominion of Canada, have invented certain new and useful Improvements in Harness Back-Bands; and I do hereby declare that the following is a full, clear, and exact description of the construction and operation of the same.

10 The invention relates to a very simple but effectual device in the manufacture of harness back-bands that will be much stronger than the present method of construction, and will enable repairs to be made when required in 15 that part of the harness without ripping seams, as is now usually the case.

By reference to the drawings forming part of this specification it will be seen that Figure 1 represents an elevation of back-band. 20 Figs. 2 and 5 are side views. Fig. 3 is a perspective view of the holder or stiffener plate hook. Fig. 4 is a perspective view of the cover-plate. Fig. 6 is a nut.

A represents the back-band, provided with 25 a square opening, *m*, cut in it, as seen at Fig. 5. *d* is the pad or bearer on the under side of the back-band. *e* is a metallic plate, about six inches long and one inch wide, bent, as shown at Fig. 3, and having its lower end 30 curved upward in the form of a hook. This hooked plate is passed through the opening *m*, leaving the hooked end projecting on the outside of the opening *m*. The inner end under the flap is secured to it by the terret-screw *h*, passing through it at the hole *n*, and secured by a socket-nut, *i*. The shaft bearer-strap *k* has a D-hook attached to it, which is 35 made to catch on the projecting hook of the holder-plate *e*, and to prevent its working off said hook I construct a tapering side flanged 40 cover-plate, *f*, similar to that shown at Fig. 4, to fit snugly against the edge of the said hook and cover the opening *m*, and secure it in that position by means of the screw *p* passing 45 through it and the metallic holder-plate *e* and screwed by a nut, *q*, on the under side of the back-band, as shown at Fig. 1. The flanges *r* on the sides of the said cover-plate *f* slip over the holder-plate *e* and form a fine 50 finish, while the plate itself prevents the D-hook from ever getting loose.

In the present method of constructing back-bands, when repairs are needed, it costs a great deal of time and labor to fix this part of 55 the harness, for the parts being covered on

the under side with the pad *d* or panel had to be ripped open and the necessary repairs made and sewed up again. By my device all this unnecessary labor and waste of time can be avoided, for if the D-hook breaks, or the strap *k* breaks away from the said D-hook, all that is necessary to do is to remove the plate *f*, by turning the screw *p*, without touching the pad underneath, and replace the D-hook and strap after repairing; or should the 65 end of the plate *e* wear off it can easily be removed by unscrewing the terret-screw *h* and screw *p*, and the said holder-plate pulled out from the back-band, replaced by a new one, and fastened by the said screws *h p*. 70

It may be observed that the nuts *i* and *q* are made similar to those shown at Fig. 6, and are made fast to the back-band or other plates that may be employed in that part of the harness, so that a new holder-plate, *e*, may be 75 inserted any time and no difficulty experienced in fastening it with the said screw and nuts.

The advantages of my device are: It is stronger and more durable than the old method, as the parts are made of metal instead of all leather. It is cheaper in the long run, as it saves time and stock. It is light, neat, compact, and needs no jockey. It is self-adjusting, fastened with screws, and requires no 85 nailing or fitting. It is less difficult to repair, as the parts are so easy to be removed.

Having thus described my device and its advantages, what I claim as my invention is— 90

1. In combination with a back-band, *A*, the metal holder-plate *e*, formed as shown, and made to pass through an opening in the back-band, and secured at one end by the terret-screw *h* and the forward end by the screw 95 *p*, substantially as specified.

2. In a back-band, *A*, and in combination with the holder-plate hook *e*, the cover-plate *f*, substantially as and for the purpose specified. 100

3. The combination of the back-band *A*, holder-plate hook *e*, plate *f*, screws *h p*, and nuts *i* and *q*, substantially as and for the purpose specified.

Dated at Hamilton, Ontario, Dominion of 105 Canada, this 18th day of February, A. D. 1885.

In presence of—

W. M. BRUCE,
J. W. POTTER.

WILLIAM HARDY.
